HYDRAULIC UNIT

Chite S. Lee, Detroit, Mich.

Application September 23, 1948, Serial No. 50,843

5 Claims. (Cl. 60—52)

1

This invention relates broadly to new and useful improvements in hydraulic machines and more particularly to a novel mounting arrangement for the instrumentalities which control the operating cycle of such machines.

An important object of the present invention is to provide a control panel assembly for hydraulically operated machines, which panel includes all or substantially all of the equipment or instrumentalities for operating machines.

Another object of the invention is to provide a control panel assembly of the above-mentioned character wherein the instrumentalities are all mounted on and associated with the panel so as to provide a unitary assembly.

Still another object of the invention is to provide a control panel assembly of the above-mentioned character that can be easily and expeditiously mounted on or removed from the machine.

Yet another object of the invention is to provide a control panel assembly of the above-mentioned character wherein certain of the instrumentalities are uniquely located on the panel so as to connect or align automatically with co-operative machine parts or elements when the assembly is mounted on the machine.

A further object of the invention is to provide a novel arrangement for the control parts of hydraulic machines on a mounting panel, which panel assembly is capable of standardization so that a panel assembly can be easily and quickly replaced by a substitute assembly in the event failure occurs in some part of the control equipment or in the event it is necessary to repair or replace any part of the control equipment.

Other objects and advantages of the invention will be apparent during the course of the following description.

In the drawing forming a part of this specification and wherein like numerals are employed to designate like parts throughout the same,

Fig. 1 is a side elevational view of a hydraulically operated machine equipped with a control panel assembly embodying the present invention.

Fig. 2 is a longitudinal sectional view through the machine shown in Fig. 1.

Fig. 3 is a front elevational view of the panel assembly with the cover removed,

Fig. 4 is a top plan view thereof,

Fig. 5 is a diagrammatic view of the hydraulic circuit for controlling operation of the machine, and

Fig. 6 is a diagrammatic view of the electrical circuit for controlling the operation of the various hydraulic instrumentalities.

2

Many automatic machine tools are operated hydraulically. Various instrumentalities such as pumps, valves, metering devices and control circuits are employed for each machine. The number and arrangement of these instrumentalities usually varies somewhat depending upon the nature of the machine and the operation to be performed.

Heretofore the various instrumentalities in the 10 operating and control circuits have been mounted more or less indiscriminately on the machine. Apparently the location and mounting of each instrumentality has been determined primarily by convenience and the particular function it is 15 to perform. As a result, the operating and control devices are disposed at various points over the entire machine, and a failure of one device renders the entire machine inoperative until the device can be repaired or replaced. Frequently, 20 it is actually necessary to dismantle parts of the machine in order to gain access to a particular device. When this condition prevails, the machine is out of operation for a considerable period of time.

25 Further, there are many instances where large automatic machines are made up of a number of small units, each of which performs a different operation on the work. When one of the small units is rendered inoperative for any reason, the entire machine is out of commission. Thus the failure of a hydraulic pump, for example, on one of the small individual units, may render the entire machine inoperative for an entire day or longer.

35 When a machine is out of operation, production is curtailed and man hours are lost. Also, the loss of a key machine may affect the operation and production of other machines in the plant. Thus, a solution to the problem of quickly making 40 repairs on or replacing parts of the hydraulic and electrical operating and control circuits of these machines will to a large extent obviate the above difficulties.

The present invention comprises a mounting 45 arrangement for the various hydraulic and electrical instrumentalities which operate and control machines of the above-mentioned character. It is contemplated that all of the instrumentalities be mounted on a single panel and that the panel be arranged and mounted on the machine in such a way that any instrumentalities which cooperate with parts of the machine will be automatically connected to or aligned with such parts when the panel is mounted on the machine. Also, it is contemplated that the various instrumentalities be uniquely combined and 50 55

correlated on the panel so that the various hydraulic and electrical circuits can be completed within the confines of the panel. By reason of this arrangement, it requires but a few minutes to mount or remove a panel. Since a large number of machines in a single plant will use identical control panels, it thus becomes expedient and practicable to maintain replacement panels. If a hydraulic pump or other instrumentality for operating or controlling one of the machines is rendered inoperative or faulty in operation for any reason, an entirely new or properly serviced panel assembly can be easily and quickly substituted for the panel assembly of such machine. The replacement can be accomplished in a few minutes and the machine will be out of service for only a very short time. The panel assembly having the faulty or inoperative equipment can then be resuscitated at leisure.

In the drawing I have shown a hydraulically operated, electrically controlled machine which is typical of those for which the present invention is primarily adapted. The machine here shown comprises a head 10 mounted for longitudinal sliding movement on a base 12. A spindle 14 extends longitudinally through the head 10, and it is supported for rotation by bearings 16 and 18 in the end walls 20 and 22 of the head. At the forward end of the spindle 14 is a coupling 24 which is adapted to receive a tool or tool holder (not shown) according to conventional practice. Surmounting the head 10 is a motor 26 which rotatably drives the spindle 14 through the medium of pulleys 28 and 30 and endless belts 32. A guard 34 is provided for the pulleys 28 and 30 and endless belts 32. Thus, a tool carried by the spindle 14 is rotatably driven by the motor 26, and the rotating tool can be advanced or retracted axially by moving the head 10 on the base 12.

In order to advance and retract the head 10 positively on the base 12 I provide a hydraulic motor which includes a cylinder 36 fixed on the head and a piston 38 fastened to the base 12. The cylinder 36 is arranged with its axis parallel to the direction of travel of the head 10. As best shown in Fig. 2, the cylinder 36 extends downwardly into the base 12 and receives the piston 38 having a piston rod 40 which is fastened to the forward wall 42 of the base. Hydraulic liquid is admitted into or discharged from the cylinder 36 ahead of the piston 38 through a passage 44 and is admitted into or discharged from the cylinder behind the piston through a passage 46. Since the piston 38 is stationary, hydraulic liquid admitted into the cylinder 36 through passage 44 will advance the cylinder to the left from the position shown in Fig. 2 and consequently the head 10 to which it is attached. Conversely, hydraulic liquid admitted into the cylinder 36 behind piston 38 retracts the cylinder and the associated head 10. In the drawing, the head 10 and cylinder 36 are shown fully retracted on the base 12.

In the machine here shown by way of illustration, the head 10 is hollow and serves as a tank or reservoir for the hydraulic liquid which conveniently may be charged thereto through a filler pipe 48. Preferably, a tubular housing 50 is provided around the spindle 14 between bearings 16 and 18. The housing 50 is spaced circumferentially from the spindle so as not to interfere with rotation of the latter, and the ends thereof are fastened to the end walls 20 and 22 by sealing members 52 and 54 respectively. If

necessary or desirable, suitable additional seals (not shown) may be provided around the bearings 16 and 18.

As suggested, the hydraulic apparatus for directing and controlling the flow of liquid to the cylinder 36 and electrical apparatus for operating the hydraulic equipment are grouped together on a panel assembly 56, and the latter is bolted or otherwise fastened to the head 10 over an opening 58 in one side thereof. Suitable sealing strips 57 are provided around the margin of the panel to prevent leakage of hydraulic liquid from the tank. Since the panel assembly 56 is mounted on the outside of head 10, it is readily accessible and can be easily and quickly attached to or removed from the machine. All of the hydraulic and electrical instrumentalities are mounted on the panel and consequently are applied to or removed from the machine with the panel assembly.

All hydraulic equipment of this type includes a pump unit 60 or the like for creating hydraulic pressure in the system. It is a particular feature of this invention that the pump unit 60 is so located on the panel assembly 56 that it is automatically connected to a suitable rotary drive mechanism when the assembly is mounted on the head 10. In addition to the pump unit 60, various valves and the like are employed to control flow of the hydraulic liquid.

In connection with the drive for the pump unit 60, it will be observed that the head 10 of the hydraulic unit here shown is provided with a second wall 62 behind and spaced from the end wall 22. If desired, a second bearing 64 for the rearward end of spindle 14 may be carried by wall 62. A gear 66 is keyed to the spindle 14 between walls 22 and 62, and this gear meshes with a gear 68 having oppositely extending stud shafts 70 and 72 which are rotatably supported in walls 22 and 62 by bearings 74 and 76 respectively. Stub shaft 70 extends forwardly through wall 22 and the projecting end thereof is equipped with a coupling 76 which is positioned to receive the driven shaft 78 of the pump unit 60 automatically when the panel assembly 56 is mounted on the head 10.

I have here shown the pump unit 60 mounted on the inside of the panel assembly 56 so that it is disposed bodily in the fluid reservoir of the hydraulic systems. The driven shaft 78 is adapted to telescope into the coupling 76 and it conveniently is provided with splines which interengage correspondingly shaped splines in the coupling to establish a direct rotary drive therebetween.

To connect the pump unit 60 with the drive mechanism, it is merely necessary to place the panel assembly 56 against the side of housing 10 and then push the entire assembly to the right as viewed in Figs. 1 and 2 to engage the driven shaft 78 with the driving coupling 76. After the pump unit 60 has been connected to the power drive in the manner described, the panel assembly can be easily and quickly bolted to the housing.

The machine here shown is adapted to advance rapidly on a traverse stroke to bring the tool up to the work and to then advance relatively slowly on a feed stroke as the tool is brought against the work. After the feeding stroke is completed, the head is withdrawn rapidly to its initial position. Consequently, the panel assembly 56 is equipped with hydraulic instrumentalities and

electrical controls for effecting the series of movements described below.

Reference is now had to Fig. 5 which shows the hydraulic equipment for operating the machine. The pump unit 60 here shown is a dual unit which comprises a traverse pump 80 and a feed pump 82. The traverse pump 80 has an inlet 84 and an outlet 86 and is adapted to charge a relatively large volume of liquid under relatively low pressure to the hydraulic system. The feed pump 82 has an inlet 88 and an outlet 90 and is adapted to charge a relatively low volume of liquid under relatively high pressure to the hydraulic system. Both pumps 80 and 82 conveniently can be driven simultaneously from the same shaft 76 according to conventional practice. As suggested, the pump unit 60 is mounted on the inside of a panel 92.

The discharge outlet 86 of the traverse pump 80 is connected to the inlet port 94 of a conventional spring-centered, solenoid pilot-operated four-way valve 96 by a conduit 98. A relief valve 100 in conduit 98 limits maximum pressure in the conduit to about 325 lbs. per square inch. The discharge outlet 90 of feed pump 82 is connected to the inlet 102 of a conventional two-way valve 104 by a conduit 106. A relief valve 108 in conduit 106 limits maximum pressure therein to about 1000 lbs. per square inch. Also, the discharge outlet 90 is connected to the pilot port 110 of four-way valve 96 by a branch conduit 112. Thus, since feed pump 82 is continuously operated, it maintains pilot pressure at all times on the four-way valve 96.

The four-way valve 96 has two discharge ports 113 and 114 which open into the tank or reservoir. Also, the four-way valve 96 has two discharge ports 116 and 118 which connect to opposite ends of the cylinder 36. Specifically, outlet port 116 is connected by conduits 120 and 122 to the passage 44 at the forward end of cylinder 36, and outlet port 118 is connected by conduits 124 and 126 to the passage 46 which communicates with the rearward end of the cylinder. A relief valve 128 at the juncture of conduits 124 and 126 limits maximum pressure therein to about 200 lbs. per square inch.

Cylinder 36 and head 10 associated therewith can be made to advance or retract relatively rapidly by operating valve 96 to connect the inlet port 94 either with the port 116 or the port 118. When the inlet port 94 is connected to outlet port 116, hydraulic liquid from traverse pump 80 is directed to the forward end of cylinder 36 and the unit advances. On the other hand, when inlet port 94 is connected to outlet port 118, hydraulic liquid from traverse pump 80 is directed to the rearward end of cylinder 36 and the head retracts.

The two-way valve 104 is provided with two outlet or discharge ports 130 and 132. Outlet 130 is connected directly to the tank through a pressure-relief valve 134 which normally is set to yield at a pressure of about 50 lbs. per square inch. The other outlet 132 is connected to the inlet 136 of a conventional flow-control valve 138 by a conduit 140. The flow-control valve 138 is provided with two outlets 141 and 142. Outlet 141 discharges excess liquid in the valve to the tank and outlet 142 is connected by conduit 144 to the conduit 122 which leads to the forward end of cylinder 36. When two-way valve 104 is positioned to effect communication between inlet 102 and outlet 130, the output of feed pump 82 is

directed back into the tank through relief valve 134. However, the latter functions to maintain at least 50 lbs. pressure in conduits 106 and 112 and thus maintains operating pressure on the pilot of four-way valve 96. On the other hand, when two-way valve 104 is positioned to effect communication between inlet 102 and outlet 132, liquid from the feed pump 82 is directed through conduit 140, flow-control valve 138, conduit 144, and passage 44 to the forward end of the cylinder 36 to advance the latter on the feed stroke.

The flow-control valve 138 regulates the rate of flow of liquid to the cylinder 36 and thus determines the rate of advancement of the unit.

Most valves of this type are equipped with a manual control 146 which is adjustable to regulate the rate of flow through the valve. Valves of this type are conventional and their construction well known; consequently a detailed disclosure or description is not essential.

Reference is now had to Fig. 6 which shows the electrical circuit for controlling operation of the hydraulic equipment hereinabove described. Current is conducted to the apparatus from any suitable source of electrical energy through line 148 and is returned to the source through line 150.

Motor 26 is equipped with the usual starter, and current from the line 148 flows to the starter coil 152 through line 154. From the coil 152, current flows to the negative side of the circuit through lines 156 and 158, switch 160, line 161, and stop switch 162. Switch 160 is operated mechanically by the coil 152, as indicated in the drawing, and stop switch 162 is manually operated to control flow of current through the coil 152 and through the entire electrical circuit. Switch 160 is normally open, and switch 162 is normally closed as shown.

The entire circuit is energized by a starting switch 164 which by-passes switch 160. Current from line 156 flows through lines 166 and 168 through switch 164, and thence through line 170 to switch 162 and line 150. Manifestly the starting switch 164 is normally open, and it will be readily apparent that no current will flow through the starter 152 as long as the starting switch remains open. Starting switch 164 is manually operated; and as soon as it is closed, current flows through the starter 152. As soon as the circuit is completed through the starter 152, switch 160 is closed by the starter coil 152 and it remains closed after the starting switch 164 is released and until the stop switch 162 is opened.

When current is flowing through the starter 152, motor 26 is energized and it continuously drives the tool spindle 14 as well as both the traverse pump 80 and the feed pump 82. The head 10 is normally retracted as shown in Figs. 1 and 2. The four-way valve 96 normally is positioned to direct the output of traverse pump 80 to the tank discharge port 113. The two-way valve 104 normally is positioned to direct the output of feed pump 82 to the tank discharge port 130. Of course as suggested, the feed pump acts at all times through the conduit 112 to maintain operating pressure on the solenoid of four-way valve 96. Thus, with the head 10 retracted and the valves 96 and 104 positioned in the manner described, the output of traverse pump 80 and feed pump 82 is merely circulated through the valves and back to the tank. Also, it should be noted that automatic operation of the machine is controlled by three limit switches: LS1, LS2, and LS3 (Figs. 1 and 6); and, when the head 10 is fully retracted, the normally open limit switch LS1 is

closed by a dog 172. The spindle 14 and the tool driven thereby are continuously rotated, of course, and the two pumps 80 and 82 are continuously driven at all times when the machine is in operation but the machine does not begin its cycle of operation until the normally open, manually operated, cycle start switch 174 is closed.

When the cycle start switch 174 is closed, current flows from line 148 through line 176, line 178, control relay CR1, line 182, normally closed emergency return switch 184, line 186, normally closed limit switch LS2, lines 188 and 190, the mechanically closed limit switch LS1, line 192, the manually closed cycle start switch 174, lines 194, 195, and 198, and thence to the negative side of the circuit in the manner hereinabove described.

Control relay CR1 has two normally open switches CR1-1 and CR1-2. As soon as the control relay CR1 is energized in the manner described above, the two switches CR1-1 and CR1-2 are closed. Thereafter switch CR1-1 acts as a holding circuit to maintain the control relay CR1 energized after the manually operated cycle start switch 174 has been released and after the limit switch LS1 has been opened by initial advancement of the head 10. In connection with the foregoing it will be readily apparent that energization of relay CR1 and the consequent closing of switch CR1-1 permits current to flow from line 188 through line 200, switch CR1-1, and lines 202 and 204 to line 196, and thence to the negative side of the circuit. Switch CR1-2 controls the forward solenoid 206 of four-way valve 96; and as soon as this switch is closed, current flows from line 176 through lines 208, 210, 212, and 214, switch CR1-2, line 216, solenoid 206, and lines 218, 220, 222, 224, 226, and 228 to line 204 and thence to the negative side of the circuit.

Thus the forward solenoid 206 of four-way valve 96 is energized as soon as the circuit is closed through control relay CR1 and the forward solenoid remains energized until the circuit through control relay CR1 is broken. When solenoid 206 is energized it operates the four-way valve 96 to connect the inlet port 94 to discharge port 116 and to connect the port 114 to port 118. The output of transverse pump 80 then flows through the four-way valve to the forward end of cylinder 36. Hydraulic pressure in the forward end of the cylinder 36 causes the head 10 to advance. Fluid trapped in the cylinder 36 behind piston 38 is discharged to the tank in an obvious manner. Relatively little pressure is required, since the hydraulic liquid merely acts to advance the head sufficiently to bring the tool up to the work. The full capacity of the transverse pump 80 is utilized so that the initial traverse movement of the head is relatively rapid. At this stage in the operation, the two-way valve 104 is unaffected and the output of feed pump 82 continues to be circulated through the two-way valve to the tank.

The head 10 continues to advance on its traverse stroke until the normally closed limit switch LS2 engages dog 230. Limit switch LS2 has two switches, one of which is normally closed and is here designated LS2 and the other of which is normally open and is here designated LS2a. These two switches LS2 and LS2a are mechanically connected for mutual operation. As soon as the limit switch is operated by dog 230, limit switch LS2 is opened to break the circuit through control relay CR1, and limit switch LS2a is closed to complete a circuit through control relay CR2. Current then flows from line 208 through line

232, control relay CR2, line 234, the normally closed relay switch CR2-2, line 236, the normally closed limit switch LS3a, lines 238 and 240, the mechanically closed limit switch LS2a, and line 242 to line 228 and thence to the negative side of the circuit. Relay CR2 has two normally open switches, CR2-1 and CR2-2; and as soon as the relay is energized, these switches are closed.

Switch CR2-1 is in a holding circuit for control relay CR2, and it serves to maintain the relay energized after limit switch LS2a has opened by advancement of the switch actuator beyond dog 230. Thus as soon as control relay CR2 is energized, current also flows from line 238 through line 244, switch CR2-1, and line 246 to line 226 and thence to the negative side of the circuit. From the above it will be readily apparent that after limit switch LS2a has opened, current will continue to flow through switch CR2-1 to maintain control relay CR2 energized.

The other switch CR2-2 controls the solenoid 248 of two-way valve 104. As suggested, switch CR2-2 is closed as soon as relay CR2 is energized, and current then flows from line 212 through lines 250 and 252, switch CR2-2, line 254, solenoid 248, and lines 256 and 258 to line 220 and thence to the negative side of the circuit.

As soon as control relay CR1 is de-energized by operation of limit switch LS2, the relay switch CR1-2 is opened to break the circuit through the forward solenoid 206 of four-way valve 96. The spring-centered spool of the four-way valve 96 is then returned automatically to its normal position to again connect the inlet port 94 to the tank port 112. When this occurs, the output of transverse pump 80 is again circulated through the four-way valve 96 directly to the tank. As suggested, simultaneously with the above operation the relay switch CR2-2 is closed to energize the solenoid 248 of two-way valve 104. Operation of the two-way valve 104 connects the inlet port 102 with outlet port 132 and directs the output of feed pump 82 to the forward end of the cylinder 36 through the flow-control valve 138. The feed pump 82 supplies relatively high hydraulic pressure to the cylinder to advance the head 10 during that portion of the cycle of operation when the tools are cutting through the work. Also, advancement of the head during this portion of the cycle of operation is relatively slow and the rate of movement is controlled by the flow-control valve 138 in the manner hereinabove described.

The head 10 continues to advance until limit switch LS3 engages dog 260. As shown in Fig. 6, this limit switch comprises a normally open switch designated LS3 and a normally closed switch designated LS3a, and these switches are mechanically interconnected for mutual operation. As soon as the actuating arm of the switch engages dog 260, switch LS3 is closed and switch LS3a is opened.

As described above, switch LS3a is in the circuit which controls relay CR2; and as soon as this switch is opened, relay CR2 is de-energized. Simultaneously, relay switch CR2-2 is opened and the solenoid 248 of the two-way valve 104 is de-energized. De-energization of solenoid 248 permits the two-way valve 104 to return to its normal position so that the output of feed pump 82 is again circulated directly to the tank.

Also, as soon as limit switch LS3 is closed, a circuit is completed from line 210 through line 262, control relay CR3, line 264 and 266, the normally closed limit switch LS1a which is mechani-

cally connected to limit switch LS1, lines 268 and 270, mechanically closed limit switch LS3 and line 272 to line 224 and thence to the negative side of the circuit.

Control relay CR3 has a normally open switch CR3-1, a normally closed switch CR3-2, and a normally open switch CR3-3; and as soon as the relay is energized by closure of limit switch LS3, switches CR3-1 and CR3-3 are closed and switch CR3-2 is opened. Relay CR3 controls the return movement of the head 10 and remains energized until the head is fully retracted.

Switch CR3-2 is in the circuit which controls relay CR2, and it thus remains open to prevent energization of relay CR2 when limit switch LS2 rides over dog 230 on the return stroke of the head 10.

Switch CR3-1 completes a holding circuit which maintains relay CR3 energized after the head 10 has begun its return stroke and limit switch CR3 has backed away from and released the actuating dog 260. In this connection it will be readily apparent that energization of the relay CR3 also permits current to flow from line 268 through line 274, switch CR3-1, and line 276 to line 222 and thence to the negative side of the circuit. Thus, switch CR3-1 will maintain relay CR3 energized even after limit switch LS3 has opened.

Switch CR3-3 controls the return solenoid 278 of four-way valve 96. Thus as soon as relay CR3 is energized, current can flow from line 250 through line 280, switch CR3-3, line 282, solenoid 278, and line 284 to line 258 and thence to the negative side of the circuit. Solenoid 278 actuates four-way valve 96 to effect communication between inlet port 94 and outlet port 118 and between the two ports 112 and 116. Thus, as soon as the solenoid 258 has been energized, the output of traverse pump 80 is directed to the rearward end of cylinder 36 and the forward end of the cylinder is connected to the tank. A rapid return is desired, and the full capacity of traverse pump 80 is therefore available to retract the cylinder 36. In this connection, it will be readily apparent that fluid trapped in the cylinder head of piston 38 is discharged through the four-way valve 96 to the tank.

The head 10 continues to retract until limit switch LS1 again engages the operating dog 172. When this occurs, limit switch LS1 is closed to set up a preparatory circuit through control relay CR1 and limit switch LS1a is opened to break the circuit through control relay CR3. As soon as the latter relay is de-energized, four-way valve 96 is again returned automatically to a neutral position to circulate the output of traverse pump 80 directly to the tank. The machine has then completed its cycle of operation, and it will remain in this position until the cycle start switch 174 is again closed.

The machine can be returned to its initial position in any stage in its operation by manual manipulation of the emergency return switch 286 which is mechanically connected to the switch 184 hereinabove referred to. Switch 286 is normally open and switch 284 is normally closed. Also, it will be observed that one side of the normally open switch 286 is connected to line 264 by line 288 and that the other side of switch 286 is connected to line 198 by line 290. As suggested, switch 286 is manually operated; and, as soon as it is closed, a circuit is completed through the control relay CR3 to retract the head 10 in the manner hereinabove described. Since switch 184

is opened simultaneously with the closure of switch 286, de-energization of control relay CR1 is assured, and since relay switch CR3-2 is opened automatically when control relay CR3 is energized, de-energization of control relay CR2 also is assured upon operation of the emergency return switch. Thus the head 10 is returned automatically when emergency return switch 286 is operated, regardless of its position at the time the switch is operated.

The panel 92 preferably is in the form of a casting, and most of the conduits which form the hydraulic circuit can be formed directly in the casting to minimize leakage from the circuit or danger of rupture in any of the conduits. It is particularly desirable to form the conduits 122 and 126 directly in the panel and to so locate these conduits that they automatically register with the passages 44 and 46 at opposite ends of the cylinder 36 when the panel is mounted on the head 10. This construction eliminates the necessity of making hydraulic connections at these points and assures precise alignment of the conduits with the passages by the mere mechanical operation of fastening the panel on the head. However, it will be readily apparent that, if desired, the panel 92 can be made merely of sheet metal and the various hydraulic instrumentalities mounted thereon and connected by suitable tubular conduits.

Also, the electrical connections preferably are made through an electric terminal block 292 mounted on the panel as shown in Fig. 3 in order to maintain the panel assembly as much of a unit as possible and to reduce to a minimum the number of electrical connections that must be made when the panel assembly is mounted on or removed from the machine. All the hydraulic equipment except the pump assembly 60 and all the electrical connections to the panel preferably are made on the outside of the panel 92. All of the control equipment except the manual actuator 146 of the flow-control valve 138 are concealed behind a cover 294 (Fig. 1). The cover 294 is suitably fastened to the panel 92, and it is provided with an opening 296 through which the manual actuator 146 projects for convenient access to the operator.

When the mounting arrangement hereinabove described is adopted, a panel assembly can be removed from the machine in a very few minutes merely by disconnecting a few electrical connections at the terminal block 292 and disengaging the panel 92 from the head 10. When the hydraulic conduits which serve the cylinder 36 are formed directly in the panel in the manner hereinabove suggested, that portion of the hydraulic circuit which connects with parts outside the panel are automatically broken merely by removing the panel from the head. Also, the only mechanical connection outside the panel, i. e., the connection between the pump assembly 60 and the driving coupling 76, is broken automatically by removal of the panel from the head. No parts of the machine need be removed or disassembled in order to remove the panel assembly. Thus the mounting arrangement here shown is exceedingly convenient and will reduce from a matter of hours to a matter of minutes the time during which a machine is out of operation in the event failure occurs in the hydraulic or electrical operating or control circuits.

Having thus described the invention, I claim:

1. A mounting arrangement for hydraulic machinery of the type having a slidable part, a hy-

draulic motor for actuating said part and having ports through which hydraulic liquid passes to and from the motor, a tank for hydraulic liquid, and a drive shaft associated with said tank, a unitary assembly comprising a panel adapted to be removably attached to a wall of said tank, instrumentalities for circulating and controlling flow of hydraulic liquid carried by said panel, said instrumentalities including passages for delivering hydraulic liquid to and receiving hydraulic liquid from said hydraulic motor, said passages so located on the panel as to align exactly with and to superimpose on the ports which service said hydraulic motor when the panel is fastened to the tank, said instrumentalities also including a pump on the inner side of the panel adapted to be disposed within the tank when the panel is fastened thereto, said pump having a driven shaft and said driven shaft being located so as to interconnect with the drive shaft automatically when the panel is fastened to the tank.

2. A mounting arrangement for hydraulic machinery of the type having a slidable part, a hydraulic motor for actuating said part and having ports through which liquid passes to and from the motor, and a tank for hydraulic liquid, a unitary assembly comprising a panel adapted to be removably attached to the wall of the tank, instrumentalities for circulating and controlling flow of hydraulic liquid carried by said panel and including passages for delivering hydraulic liquid to and receiving hydraulic liquid from said hydraulic motor, said passages so located on the panel as to align exactly with and to superimpose on the ports which service said hydraulic motor when the panel is fastened to the tank.

3. A mounting arrangement for hydraulic machinery of the type having a slidable part, a hydraulic motor for actuating said part and having ports through which liquid passes to and from the motor, and a tank for hydraulic liquid, a unitary assembly including a panel adapted to be removably attached to the wall of said tank, hydraulic pump means on said panel, passages for receiving hydraulic liquid from said pump means and for delivering hydraulic liquid to said hydraulic motor, said passages having openings so located on the panel as to align exactly with and to superimpose on the ports which service said hydraulic motor when the panel is fastened to the tank, and instrumentalities mounted on and carried by said panel for circulating and controlling flow of hydraulic liquid between the pump and said hydraulic motor.

4. A mounting arrangement for hydraulic machinery of the type having a slidable part, a hydraulic motor for actuating said part and

having ports through which hydraulic liquid passes to and from the motor, and a tank for hydraulic liquid, a unitary assembly comprising a panel adapted to be removably attached to the wall of the tank, hydraulic pump means on the inner side of the panel adapted to be disposed within the tank when the panel is fastened thereto, a fluid circulating system associated with the panel for delivering hydraulic liquid from said pump means to the ports which service said hydraulic motor, valve means for controlling the direction of flow of hydraulic liquid through said system, and means operable by movement of said slidable part for controlling said valve means whereby to operate said slidable part through a predetermined cycle of operation.

5. A mounting arrangement for hydraulic machinery of the type having a slidable part, a hydraulic motor for actuating said part and having ports through which hydraulic liquid passes to and from the motor, and a tank for hydraulic liquid, a unitary assembly comprising a panel adapted to be removably attached to the wall of the tank, hydraulic pump means on the inner side of the panel adapted to be disposed within the tank when the panel is fastened thereto, a fluid circulating system associated with the panel for delivering hydraulic liquid from said pump means to the ports which service said hydraulic motor, electrically controlled valve means for controlling the direction of flow of hydraulic liquid through said system, and an electrical circuit including the electric controls of said valve means and limit switches carried by the panel, said limit switches being actuated by movement of said slidable part and operable to selectively energize the electric controls of said valve means to actuate said slidable part in a predetermined manner.
